UNITED STATES PATENT OFFICE.

LINFORD J. DAVIS, OF BATTLE CREEK, MICHIGAN, ASSIGNOR TO KEYES-DAVIS COMPANY, INC. OF BATTLE CREEK, MICHIGAN.

RECEPTACLE-COVER.

1,203,987.

Specification of Letters Patent.

Patented Nov. 7, 1916.

Application filed December 13, 1915. Serial No. 66,541.

To all whom it may concern:

Be it known that I, LINFORD J. DAVIS, a citizen of the United States, residing at Battle Creek, Michigan, have invented certain new and useful Improvements in Receptacle-Covers, of which the following is a specification.

This invention relates to improvements in receptacle covers and operating means therefor.

My improvements are especially designed by me for embodiment in garbage or waste holders and I have illustrated the same in the accompanying drawings as I have so embodied them. My improvements may, however, be readily embodied in and are advantageous for use in structures designed for other purposes.

The main objects of this invention are: 20 First, to provide an improved receptacle cover and operating means therefor. Second, to provide an improved receptacle cover and operating means therefor, which is removable bodily from the receptacles so that 25 the receptacle may be changed from time to time. Third, to provide an improved operating means and lock for receptacle covers. Fourth, to provide an improved cover operating and locking means adapted to lock 30 the cover in both its closed and open positions. Fifth, to provide an improved receptacle cover and operating and locking means which is simple in structure, easy to operate and not likely to get out of repair.

35 Further objects, and objects relating to details and economies of construction and operation will definitely appear from the detailed description to follow.

I accomplish the objects of my invention 40 by the devices and means described in the following specification.

The invention is clearly defined and pointed out in the claims.

A structure constituting a preferred embodiment of my invention is clearly illustrated in the accompanying drawing forming a part of this specification, in which:

Figure I is a side view of a structure embodying the features of my invention, the 50 cover closure being shown in its raised or open position and the operating mechanism in corresponding actuated position by dotted lines. Fig. II is a detail plan view. Fig. III is a detail vertical section on a line corresponding to the broken line 3—3 of Fig. II,

the cover clamp being shown in its disengaged position by dotted lines. Fig. IV is a detail view on the line corresponding to line 4—4 of Fig. II, showing the mounting of the hangers on the cover. Fig. V is a detail vertical section on a line corresponding to line 5—5 of Fig. I. Fig. VI is a plan view of the cover proper with the cover closure omitted. Fig. VII is a detail side view of a modified form of my invention, the modification being in the provision of a support or holder for the receptacle and the mounting of the operating lever thereon. Fig. VIII is a detail vertical central section of the structure shown in Fig. VII.

In the drawing similar reference characters refer to similar parts throughout the several views, and the sectional views are taken looking in the direction of the little arrows at the ends of the section lines.

Referring to the drawing, the receptacle 1 may be of any size and shape best suited for the purpose for which it is intended. The receptacle cover 2 is provided with an opening 3 and has a closure or lid 4 for this 80 opening. The cover 2 is provided with a peripheral flange 5, the diameter of the flange being substantially greater than the diameter of the receptacle. See Fig. III. The opening 3 of the cover has flanges 6 and 7 depending within the receptacle, the flange 7 at the rear edge of the opening being wider than the flange 6. The closure or lid 4 is provided with a flange 8 at its outer edge and a flange 9 at its rear edge. The flange 8 85 is adapted to close over the flange 5 of the cover proper.

The closure 4 is provided with a hinge member 10 secured to the top thereof and having a knuckle 11, while the cover proper 95 is provided with a hinge member 12 having knuckles 13. The pintle 14 is arranged through these knuckles to project at the sides of the cover.

The cover is detachably secured to the receptacle by means of the U-shaped spring retaining fingers 15 which are secured to the cover flange by one arm so that the other arm engages under the bead-like rim 16 at the upper edge of the receptacle and a clamp 105 comprising a hook member 17 adapted to embrace the flange and engage the rim, as shown in Fig. III, and the lever 18 pivoted on the cover brackets 19. This lever 18 has a crank-like offset 20 between the brackets 110

19 on which the hook 17 is pivoted. The pivot part of this offset is disposed so that when the lever is thrown forwardly to the position shown in Fig. III, the hook is 5 thrown into engagement with the bead and drawn up tight. The clamp is disposed oppositely to the retaining members 15 so that the cover cannot be raised from or shifted laterally on the receptacle. To release the 10 cover, it is only necessary to swing the lever 18 to the position shown by dotted lines in Fig. III, which disengages the hook and the cover can be lifted from the receptacle. I 15 preferably provide a spring 20' for holding 15 the lid in its closed position, one end of the spring being secured to the under side of the cover at 21 and the other end at the other side of the lid 22, the spring being passed under the flanges 7 and 9 of the cover 20 and lid respectively.

To automatically operate the cover closure, I provide a bail-like lever 23 pivotally mounted on the hangers 24 at 25. These hangers 24 are secured to the flange 5 of the 25 cover by rivets 26 and depend at the sides of the receptacle when the cover is in place thereon. To the flanges of the closure I secure arms 27, which arms are pivoted on the projecting ends of the pintle 24, the 30 arms having upwardly offset portions 28 to receive the pintle. The rear ends of the arms are provided with pins 29 engaging slots 30 in the levers. These slots have transverse portions 31 at their upper ends 35 extending forwardly from their longitudinal portions. Coiled springs 32 are secured to the hangers and to the forward ends of the levers and act to hold the upper ends of the levers normally rearward so that the 40 pins 29 normally lie in the transverse portions of these lever slots. When the pins are in this position, it is impossible to open the cover by lifting thereon, but the cover is readily released and actuated to open the 45 same by pressing downward on the lever which first swings the upper end of the levers forward carrying the pins 29 into the longitudinal portions of the slot and then swings the arms to open the closure. The 50 pivots for the lever and closure are preferably so disposed that the upper ends of the lever swing past the closure pivots when the closure is fully opened. When open, the closure may be locked in its open position 55 by pushing rearwardly thereon. This again carries the pins into the transverse portions of the slots. After the pins are thus engaged, the closure will remain in its open position until released by a slight movement 60 of the lever. If the closure is not manipulated to lock it in its open position, it automatically closes on the releasing of the lever.

In the modification shown in Figs. VII 65 and VIII, a support 33 is provided for the

receptacle 1. The support is provided with uprights 35 at the sides of the receptacle and the lever 36 is mounted on these uprights. The closure 37 of the cover is connected to the lever in the same manner as described in the preferred construction and its operation is the same, the structures shown in Figs. VII and VIII being an embodiment 70 of my improvements in a structure having a support or holder for the receptacle. 75

With the parts formed and arranged as I have illustrated, the structure is simple and economical to produce and very easy to operate. An effective lock is provided without the necessity for catches and the like. In 80 the embodiment shown in Figs. I to VI, the cover with its operating means can be changed from one receptacle to another very readily. In either of the embodiments the cover can be locked in its raised 85 position when desirable and when closed it is effectively locked and can not be opened by dogs or the like and will not be accidentally opened by being tipped over. This 90 renders the structure especially desirable for garbage cans and for waste receptacles in 95 shops and factories where it is desirable to have receptacles that can be readily opened and at the same time are automatically closed and locked. 95

I have illustrated and described my improvements in detail in two practical forms in which I have embodied the same. I have not attempted to illustrate and describe various other embodiments which I contemplate, as I believe the disclosure made will enable those skilled in the art to which my invention relates to embody or adapt the same as conditions may require. 100

Having thus described my invention, 105 what I claim as new and desire to secure by Letters Patent is:

1. In a structure of the class described, the combination with a receptacle, of a cover having a down-turned peripheral 110 flange of a diameter substantially greater than that of the receptacle, said cover having an opening therein and flanges at the edges of the opening projecting downwardly within the receptacle, a U-shaped cover retaining member secured by one arm to said peripheral cover flange, the other arm being adapted to engage the rim of the receptacle, a cover clamp disposed oppositely to said member and comprising a hook adapted to 115 embrace the cover flange and engage the rim of the receptacle, and a lever to which said hook is pivotally connected, said lever being pivotally mounted on said cover so that the hook pivot swings below the plane 120 of the lever pivot when the lever is actuated to engage the hook, a closure for said cover opening having a downturned flange at its edge embracing said cover flange, and a 125 downwardly projecting flange at its rear 126

edge, a hinge for said closure provided with a pintle projecting at the sides of the cover, arms pivoted on the ends of said pintle and secured to the flange of said closure, hangers 5 mounted on said cover to depend at the sides of said receptacle, a bail-shaped lever pivotally mounted on said hangers and having longitudinal slots therein with transverse portions extending forwardly at their upper 10 ends, pins on said arms engaging said slots, a spring connected to said lever and to one of said hanger members and normally holding said lever with the pins in the transverse portions of said slots, and a coiled spring 15 arranged over said flange at the rear edge of said closure and secured at one end to the under side of said cover and at its other end to the under side of said closure.

2. In a structure of the class described, 20 the combination with a receptacle, of a cover having a down-turned peripheral flange of a diameter substantially greater than that of the receptacle, said cover having an opening therein, a U-shaped cover 25 retaining member secured by one arm to said peripheral cover flange, the other arm being adapted to engage the rim of the receptacle, a cover clamp disposed oppositely to said member and comprising a hook adapted 30 to embrace the cover flange and engage the rim of the receptacle, and a lever to which said hook is pivotally connected, said lever being pivotally mounted on said cover so that the hook pivot swings below the plane 35 of the lever pivot when the lever is actuated to engage the hook, a closure for said cover opening having a downturned flange at its edge embracing said cover flange, a hinge for said closure provided with a pintle projecting at the sides of the cover, arms pivoted on the ends of said pintle and secured to the flange of said closure, hangers 40 mounted on said cover to depend at the sides of said receptacle, a bail-shaped lever pivotally mounted on said hangers and having longitudinal slots therein with transverse portions extending forwardly at their upper ends, pins on said arms engaging said slots, a spring connected to said lever and 45 to one of said hanger members and normally holding said lever with the pins in the transverse portions of said slots.

3. In a structure of the class described, 55 the combination with a receptacle, of a cover having a downturned peripheral flange of a diameter substantially greater than that of the receptacle, said cover having an opening therein and flanges at the edges of the opening projecting downwardly 60 within the receptacle, a U-shaped cover retaining member secured by one arm to said peripheral cover flange, the other arm being adapted to engage the rim of the receptacle, a cover clamp disposed oppositely to said member and comprising a hook 65 adapted to embrace the cover flange and engage the rim of the receptacle, and a lever to which said hook is pivotally connected, said lever being pivotally mounted on said cover so that the hook pivot swings below the plane of the lever pivot when the lever is actuated to engage the hook, a closure for said cover opening, a hinge for said closure, a pair of hangers mounted on said cover to depend at the sides of said receptacle, a lever pivotally mounted on said hangers and having operating connections with said closure, and a closing spring for said closure.

4. In a structure of the class described, the combination with a receptacle, of a cover having a downturned peripheral flange of a diameter substantially greater than that of the receptacle, said cover having an opening therein, a U-shaped cover retaining member secured by one arm to said cover flange, the other arm being adapted to engage the rim of the receptacle, a cover clamp disposed oppositely to said member and comprising a hook adapted to embrace the cover flange and engage the rim of the receptacle, and a lever to which said hook is pivotally connected, said lever being pivotally mounted on said cover so that the hook pivot swings below the plane of the lever pivot when the lever is actuated to engage the hook, a closure for said cover opening having a downturned flange at its edge embracing said cover flange, and a hinge for said closure.

4. In a structure of the class described, the combination with a receptacle, of a cover having a downturned peripheral flange of a diameter substantially greater than that of the receptacle, said cover having an opening therein, a U-shaped cover retaining member secured by one arm to said cover flange, the other arm being adapted to engage the rim of the receptacle, a cover clamp disposed oppositely to said member and comprising a hook adapted to embrace the cover flange and engage the rim of the receptacle, and a lever to which said hook is pivotally connected, said lever being pivotally mounted on said cover so that the hook pivot swings below the plane of the lever pivot when the lever is actuated to engage the hook, a closure for said cover opening having a downturned flange at its edge embracing said cover flange, and a hinge for said closure.

5. In a structure of the class described, the combination with a receptacle, of a cover having a downturned peripheral flange of a diameter substantially greater than that of the receptacle, said cover having an opening therein, a U-shaped cover retaining member secured by one arm to said cover flange, the other arms of said members being adapted to engage the rim of the receptacle, a cover clamp disposed oppositely to said retaining members and comprising a hook adapted to embrace the cover flange and engage the rim of the receptacle, and a lever to which said hook is pivotally connected, said lever being pivotally mounted on said cover so that the hook pivot swings below the plane of the lever pivot when the lever is actuated to engage the hook, a closure for said cover opening, a hinge for said closure, a pair of hangers mounted on said cover to depend at the sides of said receptacle, a lever pivotally mounted on said hangers and having operating connections with said closure, and a closing spring for said closure.

6. In a structure of the class described, the combination with a receptacle, of a cover having a downturned peripheral flange of a diameter substantially greater than that

of the receptacle, said cover having an opening therein, U-shaped cover retaining members secured by one arm to said cover flange, the other arms of said members being adapted to engage the rim of the receptacle, a cover clamp disposed oppositely to said retaining members and comprising a hook adapted to embrace the cover flange and engage the rim of the receptacle, and a lever 10 to which said hook is pivotally connected, said lever being pivotally mounted on said cover so that the hook pivot swings below the plane of the lever pivot when the lever is actuated to engage the hook, and a closure for said cover opening.

7. In a structure of the class described, the combination with a receptacle, a cover having a downturned peripheral flange of a diameter substantially greater than that 20 of the receptacle, U-shaped cover retaining members secured by one arm to said cover flange, the other arms of said members being adapted to engage the rim of the receptacle, a cover clamp disposed oppositely to said retaining members and comprising a hook adapted to embrace the cover flange and engage the rim of the receptacle, and a lever to which said hook is pivotally connected, said lever being pivotally mounted on 30 said cover so that the hook pivot swings below the plane of the lever pivot when the lever is actuated to engage the hook.

8. In a structure of the class described, the combination with a receptacle, of a cover 35 having an opening therein, a cover retaining member arranged to engage the receptacle, a cover clamp disposed oppositely to said cover retaining member and comprising a hook adapted to engage the receptacle, 40 and a lever to which said hook is pivotally connected, said lever being pivotally mounted on said cover so that the hook pivot swings below the plane of the lever pivot when the lever is actuated to engage the hook, a closure for said opening, a hinge 45 for said closure provided with a pintle projecting at the sides of the cover, arms pivoted on the ends of said pintle and secured to said closure, a pair of hangers mounted 50 on said cover to depend at the sides of said receptacle, a lever pivotally mounted on said hangers and having longitudinal slots therein with transverse portions at their upper ends, and pins on said arms engaging said slots.

9. In a structure of the class described, the combination with a receptacle, of a cover having an opening therein, a cover retaining member arranged to engage the receptacle, a cover clamp disposed oppositely to said cover retaining member and comprising a hook adapted to engage the receptacle, a closure for said opening, a hinge for said closure provided with a pintle projecting 60 at the sides of the cover, arms pivoted on the

ends of said pintle and secured to said closure, a pair of hangers mounted on said cover to depend at the sides of said receptacle, a lever pivotally mounted on said hangers and having operative connections to 70 said arms.

10. In a structure of the class described, the combination with a receptacle, of a cover having an opening therein, means for detachably securing said cover to said receptacle, a closure for said opening, a hinge for said closure provided with a pintle projecting at the sides of the cover, arms pivoted on the ends of said pintle and secured to said closure, hangers mounted on said cover 75 to depend at the sides of said receptacle, a bail-shaped lever pivotally mounted on said hangers and having longitudinal slots therein with transverse portions at their upper ends, pins on said arms engaging said slots, 80 and a spring connected to said lever and to one of said hangers to hold the lever normally upward.

11. In a structure of the class described, the combination with a receptacle, of a cover 90 having an opening therein, means for detachably securing said cover to said receptacle, a pivoted closure for said opening, arms on said closure, hangers mounted on said cover to depend at the sides of said receptacle, a bail-shaped lever pivotally mounted on said hangers and having longitudinal slots therein with transverse portions at their upper ends, pins on said arms 95 engaging said slots, and a spring connected to said lever and to one of said hangers to hold the lever normally upward.

12. In a structure of the class described, the combination with a receptacle, of a cover having an opening therein, means for detachably securing said cover to said receptacle, a closure for said opening, a hinge for said closure provided with a pintle projecting at the sides of the cover, arms pivoted on the ends of said pintle and secured to said closure, hangers mounted on said cover to depend at the sides of said receptacle, and a lever pivotally mounted on said hangers and having operating connections with said arms.

13. In a structure of the class described, the combination with a receptacle, of a cover having an opening therein, means for detachably securing said cover to said receptacle, a pivoted closure for said opening, 110 arms on said closure, hangers mounted on said cover to depend at the sides of said receptacle, and a lever pivotally mounted on said hangers and having operating connections with said arms.

14. In a structure of the class described, the combination with a receptacle, of a cover closure, an arm on said closure, a pivotally mounted lever having a longitudinal slot therein with a transverse portion at its 120

upper end, a pin on said arm engaging said slot, and a spring arranged to normally hold the lever with said pin engaged in the transverse portion of said slot.

- 6 15. In a structure of the class described, the combination with a receptacle, a cover therefor provided with a pivoted closure, a hanger on said cover, means for operating said pivoted closure comprising a lever pivoted on said hanger and operatively connected to said closure and adapted to lock the closure in its closed position, said lock being disengaged by the initial actuation of the lever.
16. In a structure of the class described, the combination with a receptacle, of a pivoted closure therefor, an arm on said closure, a pivoted actuating lever having a slot therein with a transverse portion at its upper

end, a pin on said arm engaging said slot, and a spring arranged to hold said lever normally with said pin engaged in the transverse portion of said slot.

17. In a structure of the class described, the combination with a receptacle, of a pivoted closure therefor, an arm on said closure, a pivoted actuating lever having a slot therein with a transverse portion at its upper end, a pin on said arm engaging said slot. 25

In witness whereof, I have hereunto set my hand and seal in the presence of two witnesses.

LINFORD J. DAVIS. [L.S.]
